UNITED STATES PATENT OFFICE.

CHARLES WALE, OF NEWCASTLE-UPON-TYNE, ENGLAND, ASSIGNOR TO SIR W. G. ARMSTRONG, WHITWORTH AND COMPANY, LIMITED, OF NEWCASTLE-UPON-TYNE, ENGLAND.

GUN-MOUNTING AND MEANS FOR CARRYING SAME ON DECKS OF SHIPS.

1,323,129.

Specification of Letters Patent. Patented Nov. 25, 1919.

Application filed February 27, 1918. Serial No. 219,441.

To all whom it may concern:

Be it known that I, CHARLES WALE, a subject of the King of Great Britain, residing at Elswick Works, Newcastle-upon-Tyne, England, have invented a new and useful Improvement in Gun-Mountings and Means for Carrying Same on Decks of Ships, of which the following is a specification.

This invention relates to improvements in gun mountings for high angle fire and in means for carrying the same on the decks of ships.

According to this invention the trunnions of a gun are supported in bearings in a carriage carried on a gimbal frame which allows of universal motion. The gimbal frame is carried on a rotatable ring mounted on a cup-shaped base carried by an annular bracket secured to the frame of the ship, a space being left around and beneath the base which is filled with a packing of felt or other elastic material, thus allowing of a small movement which reduces the shock of recoil.

The center of gravity of the gun and carriage is vertically below the universal center and the weights are so disposed that they have a quick righting moment which checks any tendency of the axis of the gun to move out of its vertical plane. For this purpose a weight, whose lower surface is spherical, may be secured to the lower part of the carriage.

The base forms a spherical seating on to which the carriage sets back through a small distance on the firing of the gun, and the trunnions of the gun are allowed to set back a short distance axially, or the gimbal frame may be so constructed as to act as a stiff spring during the movement.

The gun is retained at the correct angle of elevation for range in the vertical plane of sight when the ship rolls by mechanism which absorbs the energy of the gun and the carriage during one half of the roll and causes such energy to act upon the gun and the carriage during the other half of the roll, the first half of the roll being regarded as from the time that the ship is on an even keel to the end of the roll from one side or the other, and the second half from the side or extreme roll back to the first position. Such mechanism may consist of a spring

under tension or compression, or of a hydraulic or similar cylinder.

The annexed drawings show a mounting and means for carrying the same made in accordance with this invention. Figure 1 is a plan, Fig. 2 is a sectional elevation and Figs. 3 and 4 show modifications.

The gun 10 has trunnions 11 supported in bearings in a carriage 12 carried on pivots 111 on a gimbal frame 13. On the gimbal frame 13 are pivots 131 and 132 carried by a rotatable ring 14. The forward pivot 131 enters a socket 133 on the ring 14, a spring washer 134 being inserted in the socket, and the rear pivot 132 enters a socket 135 mounted in a bearing 136 on the ring 14, a spring washer 137 being inserted between the socket and the ring 14. As the gun and carriage as one piece are free to turn upon the trunnions 111 in the frame 13 and the gun carriage and the frame 13 as one piece are free to turn upon the pivots 131 and 132, the gun is free to turn in any direction about the point of intersection of the axes of the trunnions and the pivots.

In the ring 14 are conical rollers 141 which run on a path at the top of a cup-shaped base 15 carried by an annular bracket 16 fixed to plates 17. Between the base 15 and the bracket 16 are two flanged rings 18 and 19 between which is a cushion 20 of elastic material. On the bottom of the carriage 12 is a weight 21 whose under surface conforms with the inner surface of the cup-shaped base 15 and the parts of the surface at 211 and 212 are so shaped as to come into contact with a projection 142 on the ring 14 and a projection 151 on the cup-shaped base respectively in order to limit the motion of the gun. When the gun is fired part of the recoil is taken up by the spring washers 134 and 137 and the elastic cushion 20, the carriage setting back upon the inner surface of the cup-shaped base 15.

A helical spring 22 is connected to the base 15 at 152 and to the weight 21 at 213. In place of the tension spring 22 a spring in compression, as shown in Fig. 3, may be used. In this case a helical spring 23 is contained in a cylinder 24 connected to a ring 241 by pivots 242, the ring being connected by pivots 243 to the base 15. The spring 23 is compressed by a flange 25 on a rod 251.

universally connected to the weight 21. Or, as shown in Fig. 4, a hydraulic cylinder 26 in which is a piston 261 whose piston rod 262 is universally connected to the weight 21, 5 may be used. The hydraulic cylinder is connected to a ring 263 by pivots 264, the ring being connected by pivots 265 to the base 15.

In these cases, as the ship rolls the mechanism absorbs the energy of the gun and 10 carriage due to the motion of the ship during one half of the roll, and gives out the energy during the other half, so that the axis of the gun is retained in the vertical plane and at the correct angle of elevation.

15 This operation is secured due to the tendency of the mass of the weight 21, the center of gravity of which is below the center of suspension of the gun, to travel too far in the direction of the roll of the ship as the speed 20 of the roll decreases and approaches zero. The storing up of energy in the connecting medium operates against this tendency and maintains the proper position of the gun in space. Also, by employing a connecting medium, the strength of which is of 25 the order of the friction of the bearings of the gun, the gun is forced to assume, when the vessel rests on an even keel, a predetermined position in space, the connecting medium compensating for the inherent variability of this position due to friction at the 30 universal center of suspension.

The mounting is trained by hand through an arm 27 pivoted at 271 to a bracket 272 35 connected to the ring 14.

A firing trigger 28 is carried on the arm 27 and is connected to the breech mechanism 29 by a flexible control 30.

For training the gun I provide a direction sight consisting of a bar 31 mounted on 40 the frame 13 in such a manner that it is rotatable about a vertical axis and having a vertical slot in it which forms the rear sight, a fine wire held vertically in a frame 311 45 forming the fore sight.

The gun is elevated by means of a screw 32 mounted in a swivel bearing 321 on the carriage 12 which screw engages with a swivel nut 33 mounted on the gun 10.

50 What I claim is:—

1. In a gun mounting, a carriage, bearings on the carriage supporting the trunnions of the gun, a gimbal frame carrying the carriage, a rotatable ring carrying the gimbal frame, a cup-shaped base carrying the rotatable ring, an annular bracket carrying the cup-shaped base and an elastic cushion between the annular bracket and the base.

2. In a gun mounting, a carriage, bearings 60 on the carriage supporting the trunnions of the gun, a gimbal frame carrying the carriage, a rotatable ring carrying the gimbal frame, a cup-shaped base carrying the rotatable ring, an annular bracket carrying the 65 cup-shaped base, an elastic cushion between

the annular bracket and the base and springs engaging with the gimbal frame.

3. In a gun mounting, a carriage, bearings on the carriage supporting the trunnions of the gun, a gimbal frame carrying the carriage and means which absorbs the energy of the gun and the carriage during one half of the roll of the ship and causes such energy to act upon the gun and the carriage during the other half of the roll. 75

4. In a gun mounting, a carriage, bearings on the carriage supporting the trunnions of the gun, a gimbal frame carrying the carriage, a cup-shaped base carrying the gimbal frame and means which absorbs the 80 energy of the gun and the carriage during one half of the roll of the ship and causes such energy to act upon the gun and the carriage during the other half of the roll.

5. In a gun mounting, a carriage, bearings 85 on the carriage supporting the trunnions of the gun, a gimbal frame carrying the carriage, a rotatable ring carrying the gimbal frame and means which absorbs the energy of the gun and the carriage during one 90 half of the roll of the ship and causes such energy to act upon the gun and the carriage during the other half of the roll.

6. In a gun mounting, a carriage, bearings 95 on the carriage supporting the trunnions of the gun, a gimbal frame carrying the carriage, a rotatable ring carrying the gimbal frame, a cup-shaped base carrying the rotatable ring and means which absorbs the energy of the gun and the carriage during one 100 half of the roll of the ship and causes such energy to act upon the gun and the carriage during the other half of the roll.

7. In a gun mounting, a carriage, bearings 105 on the carriage supporting the trunnions of the gun, a gimbal frame carrying the carriage, a rotatable ring carrying the gimbal frame, a cup-shaped base carrying the rotatable ring, an annular bracket carrying the cup-shaped base, an elastic cushion between 110 the annular bracket and the base and means which absorbs the energy of the gun and the carriage during one half of the roll of the ship and causes such energy to act upon the gun and the carriage during the other half of the roll. 115

8. In a gun mounting, a carriage, bearings on the carriage supporting the trunnions of the gun, a gimbal frame carrying the carriage, spring supporting means for the gimbal frame and means which absorbs the energy of the gun and the carriage during one half of the roll of the ship and causes such energy to act upon the gun and the carriage during the other half of the roll. 120

9. In a gun mounting, a carriage, bearings on the carriage supporting the trunnions of the gun, a gimbal frame carrying the carriage, a cup-shaped base carrying the gimbal frame, spring supporting means for 130

the gimbal frame and means which absorbs the energy of the gun and the carriage during one half of the roll of the ship and causes such energy to act upon the gun and 5 the carriage during the other half of the roll.

10. In a gun mounting, a carriage, bearings on the carriage supporting the trunnions of the gun, a gimbal frame carrying 10 the carriage, a rotatable ring carrying the gimbal frame, spring supporting means for the gimbal frame and means which absorbs the energy of the gun and the carriage during one half of the roll of the ship and 15 causes such energy to act upon the gun and the carriage during the other half of the roll.

11. In a gun mounting, a carriage, bearings on the carriage supporting the trunnions of the gun, a gimbal frame carrying the carriage, a rotatable ring carrying the gimbal frame, a cup-shaped base carrying the rotatable ring, spring supporting means for the gimbal frame and means which absorbs 25 the energy of the gun and the carriage during one half of the roll of the ship and causes such energy to act upon the gun and the carriage during the other half of the roll.

30 12. In a gun mounting, a carriage, bearings on the carriage supporting the trunnions of the gun, a gimbal frame carrying the carriage, a rotatable ring carrying the gimbal frame, a cup-shaped base carrying 35 the rotatable ring, an annular bracket carrying the cup-shaped base, an elastic cushion between the annular bracket and the base, spring supporting means for the gimbal frame and means which absorbs the energy 40 of the gun and the carriage during one half of the roll of the ship and causes such energy to act upon the gun and the carriage during the other half of the roll.

13. In a gun mounting, a carriage, bearings on the carriage supporting the trunnions of the gun, a gimbal frame carrying the carriage and a spring connected to the carriage adapted to absorb the energy of the gun and the carriage during one half of 50 the roll of the ship and to cause such energy to act upon the gun and the carriage during the other half of the roll.

14. In a gun mounting, a carriage, bearings on the carriage supporting the trunnions of the gun, a gimbal frame carrying the carriage, a rotatable ring carrying the gimbal frame, a cup-shaped base carrying the rotatable ring and a spring connected 55 to the carriage and adapted to absorb the

energy of the gun and the carriage during one half of the roll of the ship and to cause such energy to act upon the gun and the carriage during the other half of the roll.

15. In a gun mounting, a carriage, bearings on the carriage supporting the trunnions of the gun, a gimbal frame carrying the carriage, spring supporting means for the gimbal frame and a spring connected to the carriage and adapted to absorb the energy of the gun and the carriage during 70 one half of the roll of the ship and to cause such energy to act upon the gun and the carriage during the other half of the roll.

16. In a gun mounting, a carriage, bearings on the carriage supporting the trunnions of the gun, a gimbal frame carrying the carriage, a rotatable ring carrying the gimbal frame, a cup-shaped base carrying the rotatable ring, an annular bracket carrying the cup-shaped base, an elastic cushion between the annular bracket and the base, spring supporting means for the gimbal frame and a spring connected to the carriage and adapted to absorb the energy 80 of the gun and the carriage during one half of the roll of the ship and to cause such energy to act upon the gun and the carriage during the other half of the roll.

17. In a gun mounting, a carriage, bearings on the carriage supporting the trunnions of the gun, a gimbal frame carrying the carriage, pivots on the gimbal frame, a rotatable ring, sockets on the rotatable ring to receive the pivots, a spring in one socket and a spring between the other socket 95 and the rotatable ring, a cup-shaped base carrying the rotatable ring, an annular bracket carrying the cup-shaped base and an elastic cushion between the bracket and the base.

18. In a gun mounting, a carriage, bearings on the carriage supporting the trunnions of the gun, a gimbal frame carrying the carriage, pivots on the gimbal frame, a rotatable ring, sockets on the rotatable 105 ring to receive the pivots, a spring in one socket and a spring between the other socket and the rotatable ring, a cup-shaped base carrying the rotatable ring, an annular bracket carrying the cup-shaped base, an 110 elastic cushion between the bracket and the base and means, which absorbs the energy of the gun and the carriage during one half of the roll of the ship and causes such energy to act upon the gun and the carriage 115 during the other half of the roll.

CHARLES WALE.
